DESIGN.

—o—
A. B. CAMERON.
PANEL.

No. 20,361.

Patented Dec. 2, 1890.

UNITED STATES PATENT OFFICE.

ALLAN B. CAMERON, OF WILLIAMSPORT, PENNSYLVANIA.

DESIGN FOR A PANEL.

SPECIFICATION forming part of **Design No. 20,361**, dated December 2, 1890.

Application filed November 12, 1889. Serial No. 330,079. Term of patent 14 years.

To all whom it may concern:

Be it known that I, ALLAN B. CAMERON, of Williamsport, Lycoming county, Pennsylvania, have invented and produced a new and original Design for Panels, of which the following is a specification, reference being had to the accompanying photograph, forming part hereof.

My design relates to an ornamental panel. Upon the surface of said panel appears a rectangular elevation A. Upon the surface of said rectangular elevation appear two smaller rectangles B C, and between said rectangles B C are grooves or channels, as D, which ra-

diate from the center E to the edges of the rectangle A. The rectangular portion A therefore appears to be divided into four equal rectangles, of which two B and C are plain and flat and the remaining two are traversed by the radiating grooves D.

I claim—

The design for an ornamental panel, substantially as herein shown and described.

ALLAN B. CAMERON.
